Patented July 29, 1919.

Inventor

PIOTR JASINSKI

By his Attorney Oscar Geier

UNITED STATES PATENT OFFICE.

PIOTR JASINSKI, OF WELLAND, ONTARIO, CANADA, ASSIGNOR OF ONE-HALF TO
WLADYSLAW CZEKINSKI, OF WELLAND, ONTARIO, CANADA.

BOAT.

1,311,350.

Specification of Letters Patent. Patented July 29, 1919.

Application filed March 30, 1918, Serial No. 225,645. Renewed June 10, 1919. Serial No. 303,252.

To all whom it may concern:

Be it known that I, PIOTR JASINSKI, a subject of the Emperor of Austria, residing at Welland, Province of Ontario, and Dominion 5 of Canada, have invented certain new and useful Improvements in Boats, of which the following is a specification.

This invention relates to improvements in boats such as are used by life savers and 10 others, and has as its special object the provision of a boat which is substantially non-sinkable and which can be overturned only with great difficulty.

Another object is to provide a boat in 15 which passengers may be seated under cover, seats being also provided for those who propel the boat by means of oars.

A still further object is to provide a hollow platform rigidly united to the hull of 20 the boat at its bottom, the platform acting as a reservoir for air and also preventing rocking of the boat.

These and other objects are attained by the novel construction and combination of parts 25 hereinafter described and shown in the accompanying drawing, forming a material part of this disclosure, and in which

Figure 1 is a side elevational view showing a boat made in accordance with the invention.

Fig. 2 is a top plan view of the same, and

Fig. 3 is an enlarged transverse sectional view taken on line 3—3 of Fig. 1.

An ordinary form of boat structure is indicated having sides 10, curving upward and outward from the keel 11, the boat having a curved stern 12 and an acute point 13 at the bow as is usual.

Arranged within the boat are a plurality 40 of seats 15, the rear seat 16, being arranged convenient to the steering handles 18, through which motion is communicated to the rudder shaft 19, and rudder 20. A semi-conical roof or covering 22, provided with windows 23, is arranged at the front part of the boat, in which may be provided seats for the passengers who, by reason of the covering, are protected against the vicissitudes of the weather, this covering being rigidly engaged

with the gunwale of the boat in an ordinary 50 manner.

A hollow rectangular platform 25, is disposed below the boat, the same extending laterally slightly beyond the outline of the boat and also in advance of the point of the 55 same. This platform is preferably made of relatively thin sheet metal formed on its upper surface into two oppositely disposed leaves or plates 26 to the outline of the lower part of the boat disposed between the 60 raised elements exterior of the boat.

Reinforcing material 27, interposed between the plates and hull are held in place by the inturned upper edges 28, of the plates 65 26, which are reentrantly turned and fitted to recesses 29, formed in the sides of the boat.

A rearwardly extending projection 30 is formed centrally with the platform and furnishes an outboard support for the rudder 70 shaft 19.

From the foregoing it will be seen that the platform 25, is rigidly engaged with the lower portion of the boat upon both sides so as to become a component part of the same, 75 and, due to the extended area of the platform, it is substantially impossible to overturn the boat when loaded and within the water. At the same time it will be obvious that the air contained in the platform 25 80 furnishes a buoyant support for the boat rendering it practically unsinkable.

Having thus described my invention what I claim as new and desire to secure by Letters Patent, is.

1. In combination with a boat, of a platform extending longitudinally therebelow, said platform having a greater sectional area than that of the boat, and means for securing said platform to said boat.

2. In a boat, the combination with the body thereof, of longitudinal channels formed in the sides of said body, hook shaped engaging elements in said channels and a hollow platform formed with said 95 hooked shaped elements and said platform extending longitudinally of the body to a point beyond its sides and front end.

3. In a boat, the combination with the body thereof, seats secured therein, and a steering means comprising a handle and rudder, of a hollow platform arranged below the keel of said boat, recesses formed longitudinally in the sides of said body, plates rising from said platform engageable

within said recesses, and a foot support for said steering rudder engaged with said platform.

In testimony whereof I have affixed my signature.

10

PIOTR JASINSKI.
